US00D355412S

United States Patent [19]

Rak et al.

[11] **Patent Number:** Des. 355,412[45] **Date of Patent:** ** Feb. 14, 1995

[54] **RADIO PACKET MODEM FOR WIRELESS LOCAL AREA NETWORKS**

[75] Inventors: **Roman P. Rak**, Delta; **William E. Fenton**, Surrey, both of Canada

[73] Assignee: **Motorola**, Schaumburg, Ill.

[**] Term: **14 Years**

[21] Appl. No.: **18,476**

[22] Filed: **Feb. 7, 1994**

[52] U.S. Cl. **D14/107; D14/137;**
D14/242; D14/299

[57] **CLAIM**

The ornamental design for a radio packet modem for wireless local area networks, as shown and described.

DESCRIPTION

FIG. 1 is a top front, and right side perspective view of a radio packet modem for wireless local area networks showing our new design;

FIG. 2 is a bottom side elevational view thereof;

FIG. 3 is a rear side elevational view thereof; and,

FIG. 4 is a left side elevational view thereof.

FIG. 1

FIG. 2

FIG. 3

FIG. 4
